UNITED STATES PATENT OFFICE.

HENRY L. GUENTHER, OF LOS ANGELES, CALIFORNIA.

SEAMING HEAD FOR CAN MACHINERY.

Application filed December 21, 1921. Serial No. 523,823.

To all whom it may concern:

Be it known that I, HENRY L. GUENTHER, a citizen of the United States, residing at Los Angeles, in the county of Los Angeles and State of California, have invented new and useful Improvements in Seaming Heads for Can Machinery, of which the following is a specification.

This invention relates to can capping machines and particularly pertains to improvements in seaming heads of the type used in my machine disclosed in a co-pending application entitled "Double seaming machine" and filed concurrently herewith, Serial No. 15 523,822.

It is the principal object of the present invention to provide a seaming head adapted to be used in performing the first operation of a double seam between the body and cap 20 of a can, said head being decidedly compact in its construction and so designed as to readily lend it for use upon a multiple spindle rotary turret machine.

The present invention contemplates the use of a central, vertical, spindle upon which a rotary seaming turret is mounted and also a rotary can support, both of said members being designed to accommodate a plurality of cans; said rotary seaming structure comprising a plurality of parallel spindles spaced equidistant relative to each other and each equipped with set of seaming rollers which may be automatically moved toward and away from the periphery of a can body.

The invention is illustrated by way of example in the accompanying drawings in which:

Figure 1 is a view in central vertical section, through the seaming turret with which the present invention is concerned.

Fig. 2 is a fragmentary view in plan showing a portion of a double seaming machine and more particularly disclosing the construction and arrangement of my seaming head.

Fig. 3 is a fragmentary view in plan through the turret, as seen on the line 3—3 of Fig. 1.

Referring more particularly to the drawings, 10 indicates a central spindle. This spindle is suitably housed in a base structure 11 and a super-frame 12. The spindle carries a sleeve 13, upon which sleeve the various rotary elements of the present invention are mounted, it being understood that

the spindle is merely used as a central arbor for the sleeve and as a driving means for the various elements of the device. Mounted at the lower end of the spindle 10 is a driving gear 14. This gear imparts rotary motion to the spindle which is transferred by a gear 15 to a plurality of spur-gears 16. The gear 15 is mounted near the upper end of the spindle and above the multiple seaming head 17. This seaming head comprises a spider 18 having four vertical bearings 19, (it will be understood that any other number of bearings might be used if desired but for convenience four has been found satisfactory). These bearings serve as rotary support for sleeve 20. The sleeve extends downwardly and carries sliding cones 21 used for a purpose which will be hereinafter described.

Extending through the sleeve 20 are shafts 22. These shafts carry pressure plates 23 at their lower ends and sleeve 20 at their upper ends receive the spur-gears 16 by which the sleeve 20 is driven. The shafts 22 are hollow and receive a stripper-rod 24. This rod carries a stripper-plate 25 at its lower end. It will be understood, that, as in most can heading machines, the member 23 and the plate 25 are adapted to rest down upon the cap while the plate 25 keeps within the annular recess formed in the top of the cap. The stripper-rod 24 may be vertically reciprocated by the action of a stripping roller 26 which is secured upon the frame structure 12 and at the top of the machine.

Expansion springs 27 are provided to normally hold this rod in its uppermost position. The shafts 22 are formed with an annular groove 30, the upper ends of which grooves receive adjusting washers 31. The washers are carried by screws 32 extending into the spider. The set screws 33 secure the shafts in position. Roller units are carried by the structure 19, and when the shafts 22 are vertically adjusted, the relation between the seaming rollers and the lower flanged ends of the seaming pressure plates 23 will be changed. These units comprise a removable frame or cage 34 carrying bearing pins 35. The bearing pins serve as pivotal mountings for roller levers 36. The upper ends of these levers are fitted with cam rollers 37, while the lower ends are provided with seaming rollers 38. Attention is directed to the fact that the cam rollers are disposed in longitudinal alignment with

the levers 36, while the seaming rollers are arranged transversely of the lower end thereof. The seaming rollers may be of any preferred design, although in the present instance they are formed with a central enlarged folder 39 having annular recesses at the opposite sides thereof, the lower-most recess occurring above an inverted frusto-conical section 40.

10 The rollers 37 which are carried at the upper ends of the levers 36 rest against the tapered face of operating cones 21. These cones are vertically slidable along the sleeve 20 and are fitted with grooves around their 15 upper ends to receive shifting yokes 42. The yokes 42 are secured to hubs 43 which are in turn pinned to operating shaft 44. The upper ends of these operating shafts are each fitted with a roller which rides along a cam 20 track 45. This cam track is secured to the super-frame 12 and is fixed relative thereto. It will thus be evident that as the turret rotates around the cam track the rollers will move there-along and will cause reciprocation 25 of operating shafts 44. This in turn will cause vertical movement in opposite direction of the cone members 21, these members having a cone shaped roller face will wedge the levers 36 outwardly and will 30 cause the seaming rolls 38 to be forced inwardly against the cans. It will be understood that springs 47 are provided to hold the upper free ends of the seaming levers 36 against the tapered face of the operating 35 cones 21.

Mounted on the lower end of the spindle 10 is the can turret 48. This turret comprises a central spider 49 which is secured to the sleeve 13 by a set bolt 50. The spider 40 is formed with a plurality of parallel hubs 51 which agree in number and are in longitudinal alignment with the bearings 18 of the upper turret structure. Each of these hubs has a vertical bore to receive a sliding 45 sleeve 52. These sleeves are provided with lower cross pins 53 carrying rollers 54 at their inner ends. Rollers 54 extend into the groove of a lower track cam 55. This cam is fixed to the base plate 11 and is so designed 50 as to produce reciprocation of the sleeve members 52 when desired. The upper ends of each of the sleeve members are formed with a central counter bore to receive a spindle 56. This spindle in each instance 55 is threaded and extends upwardly through a cap 57 where it receives a can supporting plate 58. These plates are locked in position after having been adjusted on the screw portion by means of bolt 59. The 60 lower ends of member 56 are slightly enlarged and are held by means of an adjusting nut 60. This nut is threaded into the upper end of the member 52. A counter bore 61 is formed in the lower end of the member 65 56 and receives a compression spring 62.

This spring rests upon a plug 63 which is held against the screw by an adjusting bolt 64. The sleeve 52 is prevented from rotating by the use of a key 65 which permits the sleeve to slide vertically without turning. 70

Mounted upon the main drive sleeve 13 is a driving spider 66. This spider is formed with a plurality of arms 67 each carrying a feed member 68. These feed members are in alignment with the spindles of the turret 75 and agree in number therewith. By reference to Figure 3 it will be seen that they are substantially semi-circular in formation and receive the can body. The contour of these members agrees with the circumferential face of the can bodies. Attention is particularly directed to a recess portion 69 formed at the upper end of each of these members. This portion holds the cap in alignment while it is forced upwardly into 80 a bell shaped centering member 70. 85

The centering member 70 is provided to insure that the cap and can will be in alignment and that at the same time cans which are out of round will be re-shaped. This bell shaped member is formed with an outwardly flared lower lip and a circular recess into which the stripping plate 25 and the member 23 extend. 90

In operation of the present invention the cans are turned to the first operation turret by any suitable means such as the feed spider 71 shown in Figure 3. The cans are successively delivered to the can supporting platform 58. At the instant of delivery the rollers 54 encounter a rise in the lower cam track 55. This forces the roller upwardly and lifts the corresponding sleeve 52 and the can supporting platform 58 and the can will then be projected upwardly with its associated track and into the bell member 70. Here the two elements will be held in proper relation to each other and as the turret continues to revolve the shaft 44 of the respective spindle will be moved downwardly and will act through the cone member 21 to force the seaming rollers 38 inwardly. The seaming rollers and their levers are, of course, rotating around the central vertical axis of the spindle and will thus cause the rollers to pursue a circular path of travel around the head of the can. As the cone 21 moves downwardly it will force these rollers inwardly and complete the first portion of a double seam. This operation continues while the can is carried for substantially three quarters of the circumferential travel of the turret after which it is passed off of the platform 58 and onto a platform 72 where it is moved by a star wheel 73. 100 105 110 115 120 125

It will thus be seen that in the present operation the can is substantially stationary while the rollers pass around it. This insures that the can will not "slop" and that the cap will be securely fixed thereupon 130

without danger of displacement during the operation.

While I have shown the preferred form of my invention as now known to me it will be understood that various changes in the construction, combination and arrangement of parts may be made by those skilled in the art without departing from the spirit of the invention as claimed.

10 Having thus described my invention, what I claim and desire to secure by Letters Patent is:

1. A seaming head for can capping machines comprising a can support, a rotary bell-shaped centering member adapted to fit over the mouth of a can and its cap, a pressure member movable vertically independently of the centering member and seating against the face of the cap, seaming rollers adapted to form a seam between the cap and can body, means for moving said rollers toward and away from said can, and operating means for causing the rollers to circumscribe the can.

25 2. In a can seaming machine a turret having vertically movable can receiving platforms, means for causing these platforms to move along a circular course of travel, automatic means for producing reciprocation of the platforms at predetermined points in its travel, a rotary bell-shaped centering member disposed above said supporting plate and adapted to receive a can body and its cap as projected thereinto by the upward lifting action of the supporting member, a plurality of seaming rollers disposed around the top of the can, means for causing the rollers to automatically move toward and away from the can as the can is carried 30 along its circular course of travel, and means for causing the rollers to pursue a circular course of travel around the can while travelling.

3. A first operation turret for double seaming machines comprising a supporting head carrying a plurality of separately movable can supporting platforms, a seaming head disposed thereabove and comprising a plurality of rotary centering members adapted 45 to receive cans and their caps, means cooperating with the platforms and movable vertically independently of the centering members to hold the cans and their caps in a relatively fixed position, and seaming means 50 rotating around the cans during the rotation of the turret.

4. In a first operation turret for double seaming machines, a can support, a seaming head comprising a plurality of vertical spindles adapted to exert pressure against the caps of cans, a sleeve circumscribing said spindle, means for continuously rotating the sleeve while travelling with the turret, a plurality of movable seaming rollers carried 60 by the sleeve, a plurality of rotary center-

ing members and means for moving the rollers toward and away from a can while the rollers are pursuing a circular course of travel around the can.

5. A first operation turret for double seaming machines comprising a plurality of can supporting platforms, means for producing vertical reciprocation thereof, a plurality of can clamping members disposed thereabove and against which the platforms hold cans and their caps, seaming rollers adapted to act against the circumferential edge of the can cap, a sleeve carrying said rollers, a plurality of rotary centering members, means for continuously driving said sleeve, and means for automatically causing the rollers to move toward and away from the edge of the can cap during predetermined intervals.

6. A first operation turret for double seaming machines comprising a plurality of can supporting platforms, means for producing vertical reciprocation thereof, a plurality of rotary centering members adapted to receive a can and its cap, a plurality of can clamping members disposed thereabove and held against rotary movement and against which the platforms hold cans and their caps, seaming rollers adapted to act against the circumferential edge of the can cap, a sleeve carrying said rollers, means for continuously driving said sleeve, means for automatically causing the rollers to move toward and away from the edge of the can cap during predetermined intervals, and means for automatically stripping the can caps from the upper clamping means.

7. A first operation turret for double seaming machines comprising a plurality of can supporting platforms, means for producing vertical reciprocation thereof, a plurality of rotary centering members, a plurality of can clamping members disposed thereabove and held against rotary movement and against which the platforms hold cans and their caps, seaming rollers adapted to act against the circumferential edge of the can cap, a sleeve carrying said rollers, means for continuously driving said sleeve, means for automatically causing the rollers to move toward and away from the edge of the can cap during predetermined intervals, and adjustable means for regulating the pressure of the platform and pressure plate against the opposite ends of the can.

8. A first operation turret for double seaming machines comprising a continuously rotating vertical driving member, a lower turret head fixed to said member, an upper turret head fixed to said member and disposed in spaced relation to the lower head, said lower head carrying a plurality of separate vertically movable can supporting members, a track cam circumscribing the turret driving means, and operating means disposed between the several can supporting

- members and the cam which produces vertical movement of said means, the upper head comprising a plurality of vertical spindles, seaming rollers thereon, means for continuously driving said spindles to cause the seaming rollers to pursue a circular course of travel around cans disposed upon the supporting members, means for automatically causing the rollers to move toward and away from the cans while travelling, a plurality of rotary clamping members and clamping means carried by the upper head cooperating with the supporting members to hold the cans in fixed relation thereto while the turret revolves.
10. A seaming head for can capping machines, comprising a can support, a rotary

centering member adapted to fit over the mouth of a can and its cap, seaming rollers rotating with the centering member to form a seam between the cap and the can body, and means for clamping the cap of the can including a pressure plate and a stripping plate movable vertically independently of the centering member.

20. A seaming head for can capping machines, comprising a can support, a rotary centering member adapted to fit over the mouth of a can and cap, seaming rollers adapted to form a seam between the cap and the can body, and a stripping plate movable vertically independently of the centering member.

25. 30. HENRY L. GUENTHER.

9. A seaming head for can capping machines, comprising a can support, a rotary
